S. H. Sailor & John C. Smith of Philadelphia Pa
Assignors to
Harrick & Leibrandt, of same place
Letters Patent No 639. Dated July 11th 1854

The schedule referred to in these Letters Patent, and making part of the same

To all whom it may concern

Be it known, that we, Samuel H. Sailor
& John C. Smith, of the City and County of Philadelphia and State
of Pennsylvania, have produced a new and original stove
design called the "Locy Washington Radiator" and we do

hersby declare that the following is a full, clear, and exact description of the same, reference being had to the annexed drawing forming part of this specification in which.

Figure 1. is a front elevation of the stove, and

Figure 2 a front elevation of the foot.

The design of the stove and foot being symmetrical but one half of the detail is shown.

This stove is of a hollow and swell form as shown in figure 1. it has in front two feed doors one represented by A and the other at the same distance on the left of the line x.x. to which the description of the details of the door A will apply. The door being slightly raised by a moulding a. has its panel filled up with the figures b c d. the spaces e being open. Below the hinge of the door are the leaves e from which issue the foliage and fruit f. in bas-relief and having the configuration set forth in the drawing. Under the doors is the ornament B. in bas-relief composed of the figure g bearing the projections h and i and having scrolls m sweeping from it on each side, the portion to the left of the line x.x being symmetrical with the half whose details are given in the drawing. To the right of the door A. and fruit f. is the bas-relief ornament C consisting of the scroll and j. sweep figure l and the foliage p arranged and having the configuration shown in the drawing; on the left of the line x.x is a similar ornament symmetrically situated. The corners of the stove are of the waving form shown in the drawing while from the edges run the ornaments in bas-relief D. and E. composed of the waving figures g and r bearing projections to the arrangement being as shown in the drawing. Above the doors is the row of projections S. while below the ornament B are the projections u the entire arrangement being as set forth in figure 1.

On the front of the hearth II is the scroll v bearing the projections w arranged and configured as set forth in the drawing.

The overhanging portion of the top plate T bears the curved projections x while the portion upon which the urn stands is ornamented with the scroll y and sweeps z; the configuration and arrangement being as set forth in the drawing.

The base of the urn V is ornamented in bas-relief with the figures a' and projections b' above which are the figures c'. The body of the urn is of a waving surface curving gracefully outward at the top and made up of the flutes d' and ribs e' arranged as shown in figure 1. The outward curve of the surface of the urn gives its top an undulating form into which the cover E fits it being a ribbed and fluted surface bounded by the waving edge f' fitting the top of the urn. Between the ribs are openings i, for the escape of steam. The cover is surmounted by an ornamental handle H made up of foliage and scrolls.

The configuration of the urn and arrangement of ornaments in bas-relief on the same are fully set forth in figure 1.

The foot P bears in front a semi ellipsoidal ornament m' on each side of which is a sweep n terminating in scrolls, while from between the two lower scrolls issues the foliage p; above the sweeps is foliage q; the foot terminates in three toes r' and s'; the whole arrangement and configuration of ornaments in bas-relief being as set forth in figure 2.

What we claim as original and of our own production is the design configuration and arrangement of ornaments in bas-relief on the body, foot, and urn of the "Sirra Lady Washington Radiator" as herein described and set forth in the annexed drawing. In testimony whereof we have hereunto signed our names before two subscribing witnesses.
